(57) **CLAIM**

The ornamental design for a cat house as shown and described.

DESCRIPTION

FIG. 1 is a perspective view of a cat house showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of the circled area of FIG. 2; and, FIG. 10 is an enlarged view of the circled area of FIG. 3. The broken lines depict portions of the cat house and form no part of the claimed design.

1 Claim, 10 Drawing Sheets
